UNITED STATES PATENT OFFICE.

MYRON F. HILL, OF NEW YORK, N. Y.

PERMANENT MOLD.

Application filed February 28, 1918, Serial No. 219,562. Renewed March 29, 1921. Serial No. 456,693.

To all whom it may concern:

Be it known that I, MYRON F. HILL, a citizen of the United States, residing at New York city, county and State of New York, have invented certain new and useful Improvements in Permanent Molds, of which the following is a specification, reference being had therein to the accompanying drawings, forming part thereof.

10 My invention relates to apparatus and methods for casting, particularly for casting steel, and more particularly for casting steel ships in sections.

One of the objects of my invention is a 15 form of permanent mold made of low heat conducting material having a high fusing point, above that of steel at the temperature of pouring, and so surfaced or prepared that molten metal will not adhere 20 thereto.

Another object of my invention is a mold formed of such materials having open spaces for casting the ribs and shell of a ship and provided further with collapsible members 25 to allow free shrinkage of the casting without injuring or destroying the mold or the casting.

A further object of my invention is a mold adapted to be opened with ease in 30 order to remove the casting quickly at the proper temperature, and also in order that the mold may be ready for another pouring.

A further object of my invention is to reduce the severity of action of molten steel 35 upon the surface of the mold by heating the mold and preferably keeping it hot during its time of continuous service in forming the castings.

In the drawings:

40 Figure 1 is a section of Figure 3 upon the line 1—1, showing a modification in the right portion at 66 and 67.

Figure 2 is an enlarged view of the left hand end of Figure 3, taken upon the line 45 2—2 of Figure 1.

Figure 3 is a section of a portion of Figure 1 upon the line 3—3.

Figure 4 is a detail.

Figure 5 is a vertical elevation of the 50 mold ready for pouring.

Figures 6 and 7 show the forms of fire brick and the holders therefor for the sides of the mold, Figure 6 being the form for the far side of the mold shown in Figure 5, and Figure 7 for the near side thereon.

In Figure 5 is shown a shaft 8, adapted

to be mounted upon any suitably fixed base 9 or to be swung in a hook 10 carried by a crane. Upon the shaft 8 are pivoted jaws 11 and 12, the jaw 11 secured to the bed 13 of the mold and the jaw 12 secured to the end casting 14 of the mold. The end casting is provided with fire bricks 15 and 16 held between the dove-tailing angles 17 and the separate dove-tailing forms 18 and 19. This end casting is also provided with fire bricks 20 found in place by the plate 21. The bearing in 12 is loose in a direction at right angles to the general plane of the mold.

These fire bricks, as is the case with all fire bricks intended to be used in the mold having surfaces presented to the molten steel, are prepared of material having a surface fusing point well above that of molten steel. Fire brick, for example, having a 70 surface fusing point of 3100° F. is well adapted for this purpose. The fire brick is made in molds with surfaces as smooth as possible for those surfaces of the brick intended to come in contact with molten steel 75 and such surfaces of the brick are also further prepared to prevent adhésion of the steel thereto.

After the fire bricks have been baked they may be set in the unyielding frames of the mold with any suitable filler between the bricks and the metal and between any two or more adjoining bricks, so that they form a solid bed. In this form, the surface of the fire brick that is presented to the molten steel may be baked by directing thereupon suitable heat, such for example as from any suitable gas or oil burner, until the binder or filler between the bricks near the surface of the mold has become suitably baked. 85 Thereafter graphite may be painted or rubbed on to prevent the adhesion of steel, the graphite filling all the pores of the brick and being smeared over the smooth surface. This graphic surface may or may not be 90 baked into the mold by the application of heat, as above outlined. These bricks may also have a further treatment during their process of manufacture. In the molds in which the bricks are formed graphite or 95 carborundum or any suitable material having a high fusing point and preferably containing a suitable binder such as is used in fire brick for example, and capable of receiving a surface adapted to prevent the adhesion of steel thereto, may first be deposited and the rest of the molds filled with fire 100 105 110

brick clay. After being formed these bricks may be removed and baked separately in an oven and then assembled in a mold, the crevices in the bricks being treated as above, 5 that is, by employing a filler between the bricks and covering the filler at the surface with a suitable graphite or other substance that has a high fusing point and is not adhesive to steel during the formation of cast- 10 ings.

In Figure 1 the fire bricks are shown providing the space 22 for the shell of a cast section of a ship and the space 23 for the rib of such a section, as for example, the so-called "longitudinal", well known in the Isherwood system of ship construction. Three sets of bricks are used on one side of this casting, illustrated at 24, 25 and 26. The bricks 24 and 25 are mounted upon a 20 frame or form 27 and held in place by a clamp 28 and screw threaded posts and nuts 29 through brackets formed upon the member 27. The fire bricks 26 are held between the frame members 31 and 32, which are bolted together, as illustrated at 33. Each 25 of the members 32 is L-shaped; the other portion of the L being represented at 34, carrying end bricks 35, as shown in Figure 2, forming one side of a right-angled rib 36, which may, for example, be the so-called 30 "transverse", well known in the Isherwood system. Obviously the mold thus described is adapted to form a side section of an Isherwood type ship.

35 The longitudinal rib portions of the casting are provided with bulb portions, illustrated at 37, and with stringer portions 38. The stringer portions 38 and the longitudinal portion 23 during contraction of the 40 casting approach each other and in order to allow this action without injuring the casting the various members 32-34 slide upon each other at the dividing lines 39, so that while the members 27 remain in their normal 45 positions, the members 32-34 are pushed out of position by the force of contraction of the casting. This collapsing action is resisted by springs 40 between the abutments 41 upon the members 31 and the abutments 42 upon 50 the bed 13. The abutments 42 pass through the member 32 in the slots 43, which are sufficiently large to permit all the various motions of the members 32 and 13 with relation to each other. The top of the abutment 42 is provided with a surface 44 upon which rests the member 27. This member 27 is adapted to slide upon the member 31 and if necessary upon the inclined surface 44 of the abutment 42. Rollers 45 between the 55 members 27 and 31 may be provided if desired to render the sliding action more free and frictionless. The portions 34 also are provided with rolling bearings, as indicated at 46, each consisting of a housing 47, illustrated also in Figure 2, secured to the mem-

bers 34 and adapted to carry rollers 48, rolling upon ledges 49, which may also be employed to form the dove-tailing portions to hold the bricks 35 in place. The end frame 14 is also bolted to a cover 50, which is in 70 the form of a grid having perforations 51 to allow of the insertion of clamps 52, which are adapted to be secured to ribs 53 (Fig. 1), thereby securing the bricks 54 in place. When the two parts of the mold are closed 75 on each other suitable spacers of metal or fire brick for lighting holes may be employed to establish the thickness of the shell of the casting. The mold is held properly closed by any suitable pressure.

To protect the collapsing mechanism of the mold from splashing metal, an end gate bar 55 is formed of bricks dove-tailed in suitable frame bars 56. The bars may be united by end straps shown in broken lines 80 56^a (Fig. 5) and are provided with loops 57 for the purpose of handling. The gate bar is adapted to fit over the end of the mold and protect it during pouring. This end bar is provided with suitable funnel openings 58 85 adapted to receive and direct the metal into the bulb channels 37 for the various longitudinals and corresponding portions of the stringer 38 and any other stringer that may be desired, an open space 59 being left between the bar and the end of the mold to permit the overflow of metal from the mold. When the overflow occurs the pouring is stopped and the end bar 55 is removed; some 90 non-conductor of heat being thrown over the end of the mold to delay the cooling of the metal in the channels 37 if desired. As the metal at the top is poured last and is hottest, naturally it will cool last. The channels 37 being subjected to a stream of metal will 95 also cool more slowly than other portions. The metal that reaches the shell portion 22 of the mold, particularly where the streams of metal meet between the longitudinals etc., will cool first and particularly the metal in 100 the space 36 which, being the first portion of the mold to fill up will cool first.

In order to permit the metal in the bulb space 60 to shrink towards the shell portion 22 of the casting, the bricks 61 held in a 115 dove-tailing metal frame 62 and having the cam-shaped faces 63 are pushed backward by the bulb portion of the casting against the resiliency of the springs 64, of which there should be a suitable number, the other 120 ends of the springs resting against the frame portions 14 of the mold.

In order to expedite the cooling of the bulb portion of the casting a rod 65 may be inserted in the mold, which should be of 125 such size as to be heated to a temperature above the welding point, so that it will become an integral part of the bulb. This rod, however, may be omitted and the proximity of this bulb to cooling metal be relied upon 130

for cooling this portion of the casting to the freezing point first.

As the members 27 and 32 will not slide upon each other until the metal begins to contract and until it has sufficient strength to cause the collapsing action of the mold, and as the shell portions 22 will not acquire such strength during the cooling process until after the transverse portion of the casting 36 has reached that stage, the transverse portion 36, due to contraction, frees itself from the surface of the forming bricks, thereby allowing the members 32 and 34 to slide freely.

The dividing lines between the bricks 25 and 26 may be protected by metal, as shown at 66 and 67 (Fig. 1) if desired, the metal of these brick holding portions of the mold being brought to the surface, where they may be in contact with the molten metal. In such case the surface of the frame members of the mold presented to molten steel should be smooth and covered with graphite for each pouring. As this metal will cause the liquid steel to freeze at this point sooner than at other portions of the mold the amount of frame metal exposed to the molten steel should be so small as not to crystallize the casting. In other words, the rate at which the heat travels from the molten metal into the metal frames should be less than the travel of the heat through the cast metal itself, so that when the casting is removed from the mold it will still be at an annealing temperature.

When the metal has frozen sufficiently to provide strength in the casting, such that the casting may be handled and lifted out of the mold, the operator may rotate the rod 68 in its bearings 69, upon the bed 13 of the mold, thereby swinging the arms 70, the yoke ends of which 71 engage the grooved ends of the rods 72 (see also Figure 1) thereby oscillating the levers 73 upon the pivots 74 journaled in the bed frame so that the other ends of the levers 75, through obvious pin and slot connections, are adapted to pull upon the rods 76, swiveled at 77 in the members 31, thereby withdrawing them to such an extent that the casting may be removed without the bulbs 37 catching in the mold.

When the mold is opened the abutments 42 carry with them the members 32; also the members 27, together with the bricks 24 and 25, which is brought about by the clips 79 (Fig. 4), secured to studs 80, formed upon the abutments and passing through slots 81 in the ribs 82 (Fig. 1) of the members 27.

In Figure 7 the frame member 83 is provided with an extension 84, adapted to support the peculiar form of brick 85.

In pouring, the mold may be tipped at any suitable angle, if desired, as for ex-

ample, that shown in Figure 5, the metal poured, and left in this condition until it freezes sufficiently not to run out of the end of the mold and thereafter the mold is turned over upon its back, so that the cover 50 acts as a table upon which the mold may rest, allowing the mold to be opened, as above described.

The angle at which the mold is inclined for pouring should be adjusted to such a point that the liquid metal flows freely down the bulb channels 37 without forming open spaces between the portions of metal which might thereby create blow holes in the casting. The metal should run smoothly and in solid and dense streams throughout the mold and the angle at which the mold is inclined should be adjusted to secure this result. As the surfaces are lubricated with non-adhesive coating, the metal runs freely and fast and as the fire brick preferably has a heat conductivity much less than that of green sand thinner castings may be poured than is customary with green sand.

The various parts of the mold are supplied with suitable appliances by which they may be handled by cranes to perform these various operations.

The metal is prevented from running out of the molds at the sides by forms of bricks, as shown in Figures 6 and 7, the surfaces 77 and 78 resting against the top bricks 54 at the sides of the mold respectively.

When it is desired to cast the bottom of sections of ships, the bulb 60 is omitted, as there is no bulb on the top of a "floor" of the bottom transverse. In such case the mold usually assumes a length of about half of that shown and the depth of the transverse space 36 considerably greater than that shown in this figure.

The thickness of the bricks at the various portions of the molds may be so adjusted as to assist the cooling processes in the stages above described and all the frame members should be given sufficient clearance for interrelated movements as to permit such collapsing action as may be necessary while the casting is freezing and reaching the temperature at which it is removed from the mold.

It has been found possible with green sand to cast sheets of metal as low as nine-sixteenths of an inch in considerable areas.

In casting the sections of a ship say, of ten thousand tons dead weight capacity many parts of the ship may be as thin as .40% inches in thickness. With a mold having low heat conductivity, the metal has a better chance of becoming distributed through the various parts of the molds and the various streams integrally unite than is possible with green sand. The result of this system of molding is that thinner ship sections may be cast to accommodate the

scantlings of a ship having for example the above capacity, so that a greater saving of metal is possible in the formation of such a ship than would otherwise be the case.

5 Furthermore with green sand molding the low limit of tonnage at which ships may be cast might well be eight to ten thousand tons without increasing the total weight of the steel in the hull, whereas, with my system of 10 molding smaller ships may be cast with the same result. In other words, this system of permanent molds having low heat conductivity allows the casting of ships that it 15 would not be profitable to cast with the green sand system, except for emergency purposes.

In designing a ship for casting, from fifteen to twenty per cent of metal heretofore used for connecting sheets of metal together to form the various members of the ship may 20 be transferred to the cast portions of the ship to thicken them sufficiently to bring them within the range of casting. When the casting process permits the casting of a ship with the theoretically correct scantling without increasing the parts for casting purposes, 25 a saving in weight of the steel in the hull may reach the said fifteen to twenty per cent.

This saving makes possible either the carrying of additional cargo, or results in a lesser draft for the ship, permitting greater speed or saving in power for propelling the ship. In this way factors which of themselves appear to be of slight consequence, 30 have far reaching consequences.

35 In casting ship sections for the bow and stern portions for certain forms of ships, the same castings may be utilized provided that the shell portions are cut off to fit certain dimensions of the ships. Such sections may 40 be tapered and fitted together, roughly speaking, like the pieces of a pie.

In order to utilize the hereinbefore described mold of my invention to secure sections of this form and to form lighting 45 spaces, portions of the mold are filled up with some form of filler, either metal or of baked fire brick clay, to shut off the access of the metal. Care should be taken, however, not to block the pouring channels 50 through which the metal is poured, except where those channels are not necessary for the result, in which case they may be blocked. In pouring, one or more ladles may be employed and with spouts registering with the 55 funnel-shaped holes in the pouring bar and metal may be poured into all of the bulb channels, or as many of them as may be desired for the casting, simultaneously thereby permitting rapid flowing of the metal and 60 preventing any one stream of metal from flowing so far as to cool below the point at which it will unite with another stream which it may meet.

While I have described my invention in

the form in which I prefer to put it into 65 practice, I would not have it understood that my invention is limited to the forms and details herein shown and described, but is capable of wide variations to suit the various needs of the various forms of castings, which 70 it may be desired to produce.

What I claim is:

1. A mold having a fire brick lining consisting of bricks dove-tailed in metal forms, and having said fire brick mold surface 75 rendered non-adhesive to molten metal.

2. The combination claimed in claim 1 having said mold formed of two parts pivoted for opening and closing.

3. In a mold, metal frame members 80 containing refractory lining having molding surfaces rendered non-adhesive to molten steel, said mold having rib-forming cavities for the casting and containing collapsible members to allow for contraction between 85 said rib members.

4. The combination claimed in claim 3 having said collapsible members sliding upon each other.

5. The combination claimed in claim 4 90 having said sliding parts resiliently held together.

6. The combination claimed in claim 5 having rib-forming cavities in said casting 95 at right angles to each other, and sliding parts to accommodate the contraction between any of said ribs toward each other.

7. The combination claimed in claim 3 having a space to provide a stiffening and strengthening member for the edge of said 100 rib and yielding cam-shaped members to allow for the contraction of said bulb portions towards the main portion of said casting.

8. In a permanent mold for casting a 105 sheet of metal provided with ribs, a series of two sliding members between each two ribs, one member adapted to remain in position as the casting contracts and the other adapted to slide upon the first member to 110 permit said contraction.

9. The combination claimed in claim 8 provided with mechanical means for shifting the sliding members to allow the mold to be separated from the casting.

10. The combination claimed in claim 8 having a separate gate or pouring bar adapted to be removed after pouring and before the metal freezes.

11. The combination claimed in claim 10, 120 having said space having a thick cross section to act as a conduit for the flow of liquid metal through the mold.

12. A metal mold having a refractory lining composed of fire-proof bricks.

In testimony whereof, I have affixed my signature to this specification.

MYRON F. HILL.
